UNITED STATES PATENT OFFICE.

FRIEDERICH MÜLLER, OF HARTFORD, CONNECTICUT, ASSIGNOR TO PRATT & WHITNEY COMPANY, OF NEW YORK, N. Y., A CORPORATION OF NEW JERSEY.

RELIEVING MACHINE.

Original application filed March 31, 1919, Serial No. 286,524. Divided and this application filed May 13, 1921. Serial No. 469,267.

To all whom it may concern:

Be it known that I, FRIEDERICH MÜLLER, a citizen of the United States, residing at Hartford, in the county of Hartford and 5 State of Connecticut, have invented certain new and useful Improvements in Relieving Machines, of which the following is a specification.

My invention relates to relieving machines 10 and particularly to relieving machines for operating on cutter blanks having teeth provided with non-radially arranged cutting faces.

One object of my invention is to provide 15 a machine that shall cut a blank to a rectilinear or to a non-rectilinear contour while effecting relieving movements of the cutting tool and compensating such relieving movements at different blank diameters for the 20 non-radially arranged cutting faces on the teeth of the blank.

Another object of my invention is to provide 25 a machine of the above indicated character that shall be provided with a pin and a former for guiding a cutting tool to cut the blank to a predetermined contour, means for effecting relieving movements of the tool to relieve the teeth of the blank in conformity either to helical or straight teeth, and 30 means for so varying the relieving movements as to compensate at different blank diameters for non-radially arranged cutting faces on the teeth of the blank.

A further object of my invention is to 35 provide a relieving machine with mechanism for effecting intermittent longitudinal feeding movements between the cutting tool and the blank, means for stopping the blank rotation during each feeding movement, 40 means for effecting transverse movements of the cutting tool to permit the intermittent feeding movements, means for effecting relieving movements of the tool, and means for varying the relieving movements to compensate at different blank diameters for the 45 non-radial cutting faces on the teeth of the blank.

In the art of cutting many materials and 50 particularly in cutting metals, it is preferable for many classes of work to incline the face of the cutting tool backward with respect to the direction of movement thus pro-

viding a rake or undercut which provides a 55 sharper cutting edge and enables other advantages to be obtained. To a very limited extent this principle has been applied to milling cutters, the cutter faces being inclined backward with respect to radial lines, 60 but it has not, heretofore, been deemed possible to cut a milling cutter to different diameters in accordance with a predetermined contour and to effect relieving movements 65 so that the teeth can be ground on the cutting faces without changing the effective contour of the blank. If the cutter is cut to more than one diameter and the teeth have faces which are undercut or non-radially arranged, it is essential while cutting, the 70 blank to compensate the relieving operation at the different blank diameters for the non-radial cutting faces on the teeth.

This application is a division of the application Serial No. 286,524, filed March 31, 75 1919, Patent No. 1,429,617, and contains some features disclosed in my Patent No. 1,429,611, dated September 19, 1922. The invention disclosed in this application is also disclosed in my copending application 80 Serial No. 469,266 filed May 13, 1921. In the application Serial No. 469,266 means is broadly claimed for varying the relieving operation to compensate for non-radially arranged cutting faces. Moreover the methods 85 disclosed in this application are described and broadly claimed in my application Serial No. 469,266 filed May 13, 1921. The specific methods disclosed in this application are specifically claimed in my copending application Serial No. 323,112, filed September 11, 1919. The machine disclosed in this application is adapted to form a cutter such as is described and claimed in my copending application Serial No. 323,110 filed 90 September 11, 1919.

The cutters, which are shaped by the relieving machine disclosed in this application, are adapted to cut any practical contour. Each cutter blank is cut to different 100 diameters and is adapted to cut either a rectilinear or a non-rectilinear contour. The cutting teeth on the blank are either helical or straight in form and are provided with non-radially arranged cutting faces. In 105 case the teeth are helical in form, the cut-

ting face of each tooth conforms to a helicoid. The helicoid is formed by a generatrix following a helix on a small cylinder concentric with the axis of the cutter and also following a helix on a much larger cylinder also concentric with the axis. The teeth of the cutter and the cutting faces may be inclined in either direction with respect to the axis and the degree of inclination may be varied as required.

Each tooth of the cutter is relieved along lines extending backward and inward from the outline of the non-radial cutting face. The relief lines form a continuous surface or continuous surfaces which extend from end to end of the cutter. The relief lines are properly constructed notwithstanding variations in radius at different points along the outline of the cutter and notwithstanding the variations in angular positions resulting from the non-radial helical cutting face. Preferably, the relief lines are maintained in similar relationship to each other as they extend backward and inward, the lines combining to spirals of Archimedes.

When the relief lines conform to spirals and are maintained in similar relationship as they extend backward and inward, as is preferred, it is possible to sharpen or grind the teeth of the cutter on the front cutting faces without changing the effective contour. The teeth present the same effective contour at successive non-radial helicoidal surfaces of intersection similar in form and position to the initial cutting faces. At any surface back of the initial cutting face and similar to said face, the same effective contour will be found. Therefore, if the teeth are ground on their front faces to non-radial helicoids, which are the same as the non-radial helicoids of the initial cutting faces, the effective contour will remain the same.

In the accompanying drawings:

Figure 1 is a partial front elevational view, partially in-section, of a machine constructed in accordance with my invention.

Fig. 2 is a partial plan view of the machine showing the tool-carrying slides.

Figs. 3 and 4 are detailed views of the mechanism for varying the movement of the blank carrying spindle, the views being taken from opposite sides of the machine.

Fig. 20 is a fragmentary sectional view similar in part to Fig. 11.

Fig. 21 is a development view of the cam member shown in Fig. 20.

Figs. 22, 23 and 24 are diagrammatic views showing the relation between the former members and the blanks for cutters provided with non-radially arranged cutting faces.

Referring to the drawings, a relieving machine is provided with a main frame or bed 1 upon which the other parts of the machine are mounted. A headstock 2 and a tailstock 3 are provided for carrying the blank which is to be operated on. A tool holding-and-operating mechanism 4 is provided, as shown in Fig. 1. Preferably the headstock 2 and the tailstock 3 are so arranged as to hold the blank against longitudinal movement, the tool mechanism 4 being moved longitudinally 105 along the blank in the manner to be presently set forth. When the machine is so constructed, the head stock 2 is fixedly secured to the bed, preferably being formed in part integrally therewith, as shown. The tailstock 3 is adjustable along the bed to accommodate blanks or blank arbors of different lengths.

The headstock 2 is provided with a rotatable spindle 5 mounted in suitable bearings 6 and 7. Secured to the spindle 5, in any suitable manner, is a collet chuck 8 which may be of any usual or preferred form and which is adapted to grip either the shank of the tool to be formed and relieved or an arbor upon which the tool is mounted. As illustrated, there is a blank A mounted upon an arbor B, the arbor being engaged by the chuck 8. A drive mechanism including a driving member in the form of a worm wheel 9 which meshes with a worm 10 on a transverse rotatable shaft 11, is provided for rotating the spindle 5.

The tailstock 3 may be of any usual or preferred construction, and is adjustable 130

along ways 12 and 13. The tailstock 3 can be secured in adjusted position by means of a clamp 14 which is controlled by a lever 15. The tailstock spindle 16, which carries a center 17, can be moved longitudinally by means of a screw 18 under the control of a hand wheel 19. A handle 20 is provided for clamping the sleeve in adjusted position. As shown in Fig. 2, the center 17 is adjusted into engagement with the end of the arbor B.

The tool mechanism 4 includes a carriage 21 which is longitudinally movable along ways 22 and 23 on the bed 1. A slide 24, which is mounted for transverse movement with respect to the carriage 21, carries the cutting tool. In the figures of the drawings I have shown a non-rotary lathe tool 25, and such a tool is preferable for many classes of work. However, the invention is not limited to a non-rotary tool and when preferred a rotary tool can be used. The tool 25 is preferably very narrow, but if desired a wider tool can be used when constructed in accordance with the method set forth in my Patent No. 1,348,302 dated August 3, 1920.

As stated at the outset, a machine embodying the invention is adapted for cutting a blank having a varying diameter. The diameter may vary uniformly from end to end of the blank, thus providing a uniform taper, or it may vary in any desired way so as to provide the blank with any predetermined contour differing from a straight line. The variations in the diameter of the blank are determined by moving the slide 24 together with the tool transversely, and preferably, for regulating and controlling the transverse movements, I provide a former and a former pin, one carried in fixed position on the bed 1, and the other carried by the slide 24. As illustrated, a former 26 is carried by the bed 1 and a former pin 27 is carried by the slide 24. The former 26 has exactly the same contour with which the blank is to be formed and the former pin 27 has exactly the same shape as the cutting tool 25. The pin is detachably secured to the slide, in a manner to be hereinafter set forth, so that it can be removed and another pin be substituted corresponding to a tool differing in shape from the tool 25 which is shown. A bracket 28, which is rigidly secured to the bed 1, is provided for supporting the former 26. In order to permit adjustment, the former 26 is secured to a slide 29 which is longitudinally movable along a suitable guideway 30 on the bracket, a screw 31 being provided for effecting longitudinal movement. The slide can be locked in adjusted position by means of screws 32, 32 which engage a gib 33. The slide 29 is provided with a T-slot 34 which is adapted to receive T-bolts 35 passing through the

former. Such arrangement is provided to permit the ready adjustment of the former. To further assist in holding the former in place and to prevent any possible free movement thereof, a hooked bolt 36 is provided which, when tightened, serves to draw the former back against a suitable shoulder on the slide. In practice, a former 26 is selected having the contour with which the blank A is to be formed and then by means of the slide 29 the former is adjusted longitudinally until it bears the same relation to the former pin 27 that the blank A bears to the tool 25. As the carriage 21 is moved longitudinally the slide 24 with the tool 25 is moved transversely so as to keep the former pin 27 in engagement with the former 26.

In order that the tool may be given a relieving movement to properly relieve the several teeth on the blank, it is not rigidly secured to the slide 24 but is transversely movable thereon. A slide 37, which is transversely movable along a suitable guideway, is mounted on the slide 24. A mechanism, for effecting regular reciprocating relieving movements of the slide 37 and the tool in suitable timed relation with the rotative movement of the blank is carried in part by the slide 24. In order that the tool 95 may be adjusted for blanks of different sizes, a tool-carrying slide 38 is provided which is transversely movable on the slide 37. A screw 39 which is rotated by means of a hand wheel 40, is provided for moving the slide 38. The slide 38 is provided with a transverse T-slot 41 and a tool post 42 is held in place by means of T-bolts 43 entering the slot 41. The tool post has a tool-receiving aperture provided with a horizontal top wall 44 exactly at the level of the axis of the blank. The tool 25 is positioned with its top surface engaging the horizontal wall 44 of the tool post and is held in this position by means of a wedge 45.

It will be observed that, with the construction described, the tool is maintained in parallelism as it moves longitudinally for feeding or inward and outward to follow the contour.

The relieving mechanism for moving the slide 37 together with the tool 25 includes a rotatable relieving cam 46 which is mounted on the slide 24 so as to be bodily movable therewith. As shown, the cam is 120 mounted on a longitudinal rotatable shaft 47 which is mounted in bearings 48 and 49 on a bracket 50 depending from the front of the slide 24. A lever 51 is pivoted between its ends on the slide 24 and at its lower end is provided with a roller engaging the cam 46. The upper end of the lever engages an abutment 52 on the slide 37. A coil spring 53 is interposed between the slide 37 and the slide 24, this spring tending 130

to press the slide 37 forward, thus holding the abutment 52 in firm contact with the upper end of the lever 51. It will be seen that, when the cam 46 is rotated, the lever 51 will be oscillated, thus giving a reciprocating movement to the slide 37 and to the tool 25. The shape of the cam 46 is such that the slide 37 is moved forward relatively slowly at a uniform rate so that the tool 10 may effect a relieving cut, and is then drawn back relatively rapidly so as to withdraw the tool and position it for another cut.

The cam 46 is driven in timed relation with the blank rotation, as before stated.

15 For rotating the cam, I make use of the aforesaid transverse shaft 11. A shaft 54, which is mounted partly in the main frame 1 and partly in a bracket 55 secured thereto, is positioned immediately below the shaft 20 11. The two shafts 11 and 54 are connected by means of a gear wheel 56 on the shaft 11, a gear wheel 57 on the shaft 54 and an idler gear wheel 58 meshing with the two gear wheels 56 and 57. The idler gear wheel 25 is mounted on a bearing stud 59 which is carried by an adjustable slotted arm 60. The arm 60 is carried by a hub 61 which assists in supporting the shaft 11. The speed ratio between the two shafts 11 and 30 54 can be changed by removing one or both of the gear wheels 56 and 57 and substituting other gear wheels of different diameters, it being clear that the idler gear wheel 58 can be adjusted to mesh with such differently 35 diametered gear wheels. A vertical shaft 62 is mounted in the bracket 55 and is driven from the shaft 54 by means of bevel gearing 63. The shaft 62 serves to drive a longitudinally splined shaft 65 by 40 means of bevel gearing 64. The shaft is supported partly in a bearing 66 secured to the bed and partly in bearings 67 on a depending bracket 68 secured to the carriage 21.

45 A worm 69, which is mounted on the shaft 65 between the bearings 67, is splined to the shaft. The worm 69 meshes with a worm wheel 70 which is connected with a transverse shaft 71. The worm wheel 70 and the shaft 71 are rotatably mounted in a bearing 72 formed in the bracket 68, and in a bearing 73 formed on a supplemental bracket 74 secured to the bracket 68. A bevel gear wheel 75 is slidably mounted on 50 the shaft 71 and is engaged by a bearing 76 on the aforesaid bracket 50 depending from the front end of the slide 24. The bevel gear wheel 75 and the shaft 71 are connected by means of cam slots 71' formed 55 in the shaft and pins 75' projecting from the gear wheel into the cam slots so that the bevel gear wheel is rotated, but is at the same time free to move transversely of the machine when the slide 24 is moved. The 60 cam slots 71' in the shaft 71 are so formed

as to compensate the relieving movements at different blank diameters for non-radial cutting faces. The operation of the pins 75' in the cam slots 71' will be set forth more fully hereinafter. Inasmuch as the 70 bevel gear wheels 75 and 77 are both supported by the bracket 50, they are at all times held in mesh. It will be seen that with this construction power is transmitted from the shaft 11, through the several parts 75 that have been described, to the shaft 65, and is transmitted from the shaft 65 to the shaft 47 and the cam 46, the connection between the shaft 65 and the shaft 47 being such that free transverse movements of the 80 cam and associated parts is permitted. The cam 46 is given one complete rotation for each tooth of the blank. The machine can be adjusted for blanks with different numbers of teeth by changing the gear wheels 56 85 and 57, as already explained.

As has already been stated, the machine is adapted for cutting blanks having helical teeth. In order that blanks with such teeth may be properly relieved, it is necessary to 90 effect the relieving movements of the tool in peculiar relation to the rotative movement of the blank so that the relief may be in conformity with the helical teeth. I have stated that the relieving movements of the tool are 95 effected in timed relation to the rotative movement of the blank; and, for any given position of the carriage, this timed relation is fixed and definite, but when the carriage is moved to bring the tool into a new 100 cutting position, it is necessary to vary the relation between the relieving movements of the tool and the rotative movement of the blank. For this purpose I make use of a mechanism which is in many respects similar 105 to that set forth in my aforesaid Patent 1,429,611. The present construction differs, however, in that I have so arranged the mechanism that the aforesaid relationship is varied by changing the rotative movement of the blank rather than by changing the relieving movements of the tool. While I prefer to change the blank rotation, it will be understood that my present invention in its broader aspects is not limited in this 115 respect.

In the construction illustrated, the driving member or worm wheel 9 is not connected directly with the spindle 5 but is connected indirectly by means of suitable gearing 78 120 which can be supplementally moved to change the spindle rotation. By preference, this gearing is bodily rotatable and includes a rack and pinion, the rack being longitudinally slidably in accordance with the longitudinal movements of the carriage 21. A sleeve 79 is coaxially mounted with the spindle 5 and is supported by bearings 80 and 81 in the headstock. The inner end of the sleeve 79 preferably extends into and has a 130

bearing in the outer end of the spindle 5. A frame 82 is recessed to receive the outer end of the spindle 5 and to engage the outer surface thereof. The aforesaid worm wheel 9 is rigidly secured to the sleeve 79. A shaft 83 having rack teeth formed thereon at 84 is slidably mounted in the sleeve 79. The shaft 83 is splined to the sleeve 79 so as to be rotatable therewith. A transverse shaft 85 which carries a pinion 86 meshing with the rack teeth 84, is rotatably mounted in bearings in the frame 82. A transverse shaft 87 is also rotatably mounted in the frame 82. The two shafts 85 and 87 are connected by spur gear wheels 88 and 89. A third rotatable shaft 90 is rotatably mounted in the frame 82. A worm 91, which meshes with worm teeth 92 formed in the periphery of the spindle 5 near the end thereof, is secured to the shaft 90. A gearing is provided at the side of the bracket 82 opposite from the gears 88 and 89 for connecting the shafts 87 and 90. A gear wheel 93 is mounted on the shaft 87, and a gear wheel 94 is mounted on the shaft 90. An adjustable slotted bracket 95 is mounted on the frame 82 and this carries adjustable bearing studs 96 and 97 on which are mounted, respectively, idler gear wheels 98 and 99.

30 An annularly grooved collar 100 is carried by the shaft 83 near the outer end thereof. A longitudinal guide stud 101 is rigidly secured to the main frame 1 adjacent the shaft 83. A bracket 102 having a fork 103 entering the groove in the collar 100 is slidably mounted on the stud 101. The bracket 102 is apertured to receive a longitudinal rod 104, which is connected at its right-hand end with the carriage 21. The bracket 102 may 40 be clamped to the rod 104 in any desired relative position and preferably by means of screws 105, 105 provided with handles 106.

It will be seen that, when the carriage 21 is moved longitudinally along the bed, the 45 rod 104, together with the bracket 102, will be moved at the same time and to the same extent. By reason of the engagement of the fork 103 with the collar 100 the shaft 83 is similarly moved, thus moving the rack teeth 50 84. When the rack slides longitudinally the pinion 86 is turned and this serves, by means of the gearing and the several shafts that have been described, to turn the worm 91. The rotative movement of the worm 91 55 serves to turn the spindle 5 relatively to the frame 82 and the sleeve 79. It will be understood, as before stated, that the entire gearing 78 rotates bodily with the sleeve 79. It will therefore be clear that the relative 60 movement of the spindle 5 with respect to the sleeve 79 simply serves to either increase or decrease the spindle rotation to a certain extent. However, the relative movement of the spindle 5 is determined by the longitudinal 65 movement of the rack 84, which in turn

is determined by the longitudinal movement of the carriage 21 and of the cutting tool 25 carried thereby. Inasmuch as the relieving cam 46 reciprocates the tool with a frequency which is normally uniform, and inasmuch as the spindle 5 and the blank are given a changed rotation which is in exact proportion to the longitudinal movement of the carriage and the tool, it is clear that the relieving movements are effected in such relation to the blank as to be in conformity with helical teeth.

The amount of variation of the spindle 5 and blank rotation can be changed in accordance with the degree of inclination of the 70 helical teeth by removing one or the other or both of the gear wheels 93 and 94 and substituting other gear wheels of different diameters. The idler gear wheels 98 and 99 can be properly adjusted to mesh with such 75 differently sized gear wheels. It is also possible to cause the relative movements of the spindle 5 to take place in either direction in conformity with helical teeth inclined in either direction. As illustrated, 80 the machine is adjusted for cutting teeth with left-hand helices. For cutting teeth with right-hand helices the idler gear wheel 98 is removed and the gear wheel 99 is adjusted to mesh directly with the gear wheels 85 93 and 94. When it is desired to cut a blank with straight teeth instead of helical teeth, the gearing is rendered ineffective, as for instance by loosening the clamping screws 105, thus permitting the rod 104 to slide freely 90 through the bracket 102. By loosening the clamping screws 105 it is possible to preliminarily adjust the carriage without affecting the position of the spindle 5 and blank. When the cutter and the blank have been 95 properly adjusted relatively, the handles 106 are turned to connect the carriage with the mechanism for controlling the spindle rotation.

From the foregoing description it will be 100 observed that in following helical teeth as described, the blank is rotated in each instance through a little more or a little less than one revolution, as required for right-hand or left-hand helices. It will further 105 be seen that during each rotative movement of the spindle 5 and blank a whole number of relieving movements are effected.

When cutting a blank with undercut faces, it is necessary to vary the ordinary 110 relation between the relieving movements of the tool and the rotative movement of the blank as the cutting tool moves inward or outward to conform to different blank diameters. One way of varying the relation 115 will be understood by reference to the diagrammatic Fig. 17. In this view t may be considered to be a fragmentary sectional view taken at the maximum radius r of a cutter C having undercut faces. Under the 120

125 130

control of the former and the former pin, the cutting tool 25 is at a distance r from the blank axis and is in position to engage the point of the tooth shown and to cut the proper relief line $d-d$ thereon. The tooth section at a smaller radius r' is shown at t' . For this radius, without special provision being made, the tool 25 would be in the position indicated by dotted lines at the distance r' from the blank axis. However, by reason of the inclined cutting faces on the blank, the blank tooth would not be in engagement with the tool but would be separated therefrom by the angle m' . The tool, however, would immediately start its inward relieving movement notwithstanding the fact that the blank tooth had not yet reached it, and the result would be the cutting of an incorrect relief line $d'-d'$. For a still smaller radius r'' of the blank, as shown at t'' , the result would be similar except that the point of the tooth would be separated from the tool by a greater angle m'' , with the result that the incorrect relief line $d'-d''$ would be further from the correct relief line $d-d$.

In order to avoid the errors which would occur, as shown in Fig. 17, I vary the relationship between the relieving movements of the tool and the rotative movement of the blank in such a way that the tool, as concerns its relieving movements, is always in the same position when engaged by the front edge of the tooth. This will be clear from an inspection of Figs. 18 and 19. Fig. 18 shows the tool at the same radius r' from the blank axis as was shown in Fig. 17, but the relation of the relieving movement has been so changed that the blank is in position to be engaged by the point of the tool when the relieving movement starts. The tooth is therefore cut with the correct relief line $d-d$. Similarly, in Fig. 19, the tool is shown at the same distance r'' from the blank axis as was shown in Fig. 17, but the relation of the relieving movement has been so changed that the blank is in position to be engaged by the point of the tool when the effective relieving movement starts. The tooth is therefore cut with the correct relief line $d-d$. It will be seen that the operation, as illustrated in Figs. 17 to 19, is in no way effected by or dependent on the longitudinal inclination of the cutting faces. In other words, it is immaterial whether the cutting faces be helical or straight.

The required variations in the relationship between the relieving movements of the tool and the rotative movement of the blank can be brought about either by changing (usually advancing) the blank movement or by changing (usually retarding) the tool movements. I have found it simpler, to retard the tool movements, and this is particularly desirable when means are provided as herein disclosed for chang-

ing the blank movement to conform to helical teeth. The tool movements may be properly retarded by forming the grooves 71' in the shaft 71 in accordance with the degree of undercut. Referring to Figs. 20 and 21, the shaft 71 is shown provided with inclined cam grooves 71', and the bevel gear wheel 75 is shown provided with pins 75' which are adapted to enter the grooves 71'. Fig. 21 is a development of the shaft 71 showing the inclined cam grooves. With the pins 71' in the full line position shown, which corresponds to the radius r , the cam 46 is in position to immediately start the inward relieving movement of the tool. From the description which has been given of the mechanism for driving the relieving cam, it will be recalled that for any given longitudinal position of the tool the cam is ordinarily rotated at a speed exactly in proportion to the rotative movement of the spindle and blank. When the tool is moved inward to a position corresponding to the radius r' , the normal rotative movement of the cam is retarded by an angular distance n' which corresponds to the angle m' shown in Fig. 17. When the tool moves still further inward to a position corresponding to the radius r'' , the cam is still further retarded through an angular distance n'' corresponding to the angle m'' shown in Fig. 17. The result of this retarding of the tool is to cause it to be always in the same position as concerns its relieving movements when the front edge of the tooth reaches it.

The fact that the blank may not have the maximum radius r is immaterial provided that the bevel gear wheel 75 is made to take the proper positions along the cam shaft 71. In order that this may be conveniently brought about, the former is preferably constructed so as to correspond to the radius of the blank to be cut. If the cutter C is to have a maximum radius r , the former 26^c is made with the point of maximum radius at a distance r from a given reference line, for instance the center line of the bolts 35, 35. If a cutter D is to be made having a radius r' , then the former 26^d is made with its point of maximum radius at the distance r' from the center line of the bolts. If a cutter E is to be made having a maximum radius r'' , then the former 26^e is made with its point of maximum radius at the distance r'' from the center line of the bolts. The construction of the formers in the way described insures the location of the sliding gear wheel 75 on the shaft 71 at positions corresponding exactly to the different radii of the blanks.

In the above manner, the pin and groove connection between the shaft 71 and the gear wheel 75 serves to vary the relieving movement to compensate for the non-radial cutting faces on the teeth of the blank. In my copending application, Serial No. 469,266, 130

above referred to, and in my application Serial No. 323,114, filed September 11, 1919, means are disclosed and claimed for performing a like function by varying the position of the relieving movements.

A screw 107, which engages a nut 108 carried by a bracket 109 depending from the carriage, is provided for moving the carriage longitudinally along the bed. The screw is supported at its left-hand end in a bearing 110, which is formed in a bracket 111 secured to the bed. A transverse shaft 112, which is connected with the screw 107 by means of bevel gearing 113, is mounted in the bracket 111. At the front end of the shaft 112 is a hand wheel 114 by means of which the screw may be turned manually to move the carriage. A suitable mechanism is provided for moving the carriage automatically to feed the tool from one cutting position to another. This mechanism is preferably adapted to feed the carriage intermittently, but it will be understood that as concerns certain phases of the invention I do not so limit myself inasmuch as the carriage may be moved continuously if desired. A transverse bearing pin 115 upon which is rotatably mounted a sleeve 116, is mounted in the bracket 111. A gear wheel 117, which meshes with a gear wheel 118 on the shaft 112, is loosely mounted on the sleeve 116 near the inner end thereof. A ratchet wheel 119, is connected with the gear wheel 117. Gear teeth 120, which mesh with a gear wheel 121 secured to the shaft 112, are formed on the sleeve 116 near the outer end thereof. A ratchet wheel 122, which is similar to the ratchet wheel 119, is keyed to the sleeve 116. A swinging arm 123 is loosely mounted on the hub of the ratchet wheel 122. A link 124, which is adjustably connected at its left-hand end with an oscillating crank arm 125, is pivotally connected with the arm 123 near the lower end thereof. The crank arm is secured to a transverse rock shaft 126 which is mounted in a bearing 127 and which carries at its rear end a lever 128. A roller 129, which is positioned to be engaged by a cam 130 on a longitudinally rotatable shaft 131, is carried by the lever 128 near the upper end thereof. A transverse pin 132, which carries two similar ratchets 133 and 134, is mounted on the swinging arm 123. The two ratchets 133 and 134 are adapted respectively to engage the ratchet wheels 119 and 122. Either ratchet can be thrown into or out of engagement with the corresponding wheel. The shaft 131 is rotated in the manner to be presently described, and it will be seen that at each rotation thereof the arm 128 and the crank arm 125 are oscillated. The oscillation of the crank arm 125 is transmitted to the plate 123 by means of the link 124, the extent of oscillation of the plate being adjustable by changing the connection between the link and the crank arm. By

means of one or the other of the ratchets 133 or 134, one of the ratchet wheels 119 or 122 is turned through a small angle, thus turning the shaft 112 and the lead screw 107 and moving the carriage. It will be seen that the carriage movement is relatively great when the pawl 133 is in use, and is relatively small when the pawl 134 is in use. By selecting the proper ratchet and by adjusting the crank arm connection the desired amount of carriage movement may be obtained.

Preferably the rotation of the spindle and of the blank is stopped during the feeding movement of the tool. I therefore provide two alternately acting mechanisms, one serving to rotate the spindle and the blank through one revolution, or approximately one revolution, and also serving to effect the relieving movements of the tool, and the other mechanism serving to effect the longitudinal feeding of the tool and preferably also serving to effect other movements to be described.

The mechanism for rotating the spindle and the blank has already been described in part, this mechanism including the transverse shaft 11, the worm 10 and the worm wheel 9. The machine is provided with a main power shaft 135 which is adapted to be driven in any suitable way, as for instance by means of a belt on a pulley 136. A gear wheel 137 is rotatably mounted on the shaft 135. The gear wheel 137 is connectible to the shaft 135 by means of a splined clutch element 138. The gear wheel 137 meshes with a gear wheel 139, which is mounted on a longitudinal shaft 140. A long gear wheel 141 is secured to the shaft 140. The gear wheel 141 is surrounded by a sleeve 142 which is open at the forward upper side. A bushing 143, which is slidably and rotatably mounted on the sleeve 142, is provided with ears between which a gear wheel 144 is rotatably mounted. The gear wheel 144 meshes with the aforesaid gear wheel 141 on the shaft 140. A third longitudinal shaft 145 is provided, which carries a series of differently diametered gears 146. The shaft 145 is connected with the aforesaid shaft 11 by means of bevel gearing 147. The bushing 143 can be moved angularly and longitudinally on the sleeve 142 so as to bring the gear wheel 144 into mesh with any one of the differently diametered gear wheels 146. A spring-pressed plunger 148, which is carried by the bushing 143, is adapted to enter any one of a series of apertures in the sleeve 142 so as to hold the gear wheel 144 in proper position to mesh with any desired one of the gear wheels 146. It will be seen that by this construction the shaft 145 together with the shaft 11 can be driven from the shaft 135 at any one of a series of speeds.

A short longitudinal shaft 149 is mounted in alignment with the main power shaft 135. The shaft 149 carries a clutch element which is adapted to be engaged by the afore-
5 said splined clutch element 138 on the shaft 135. When the clutch element is in its right-hand position as viewed in Fig. 16, it drives the gear wheel 137 and the several parts connected therewith. When the clutch
10 element is in its left-hand position it drives the shaft 149. A transverse shaft 150, which is suitably mounted in bearings in the bed, is connected with the shaft 149 by means of bevel gearing 151. The shaft 150 carries a worm 152 which meshes with a worm
15 wheel 153 on the aforesaid longitudinal shaft 131.

In the operation of the machine, it is desirable for the sleeve 79 and for the shaft 131 to each make one complete revolution alternately in succession. In order that the desired alternate movements of the sleeve and shaft may take place, I provide automatic mechanism for shifting the clutch element 138. The mechanism used is similar in principle to that shown and described in my Patent No. 1,273,903 for driving mechanism, dated July 30th, 1918. The clutch element 138 is provided with an annular
20 groove into which fit rollers or projections on a forked lever 154. The lever 154 is transversely pivoted on the frame and is provided with a roller 155 by means of which it may be moved. A transverse rock
25 shaft 156 is mounted in the frame above the forked lever 154. The rock shaft 156 carries at its rear end an arm 157 in which is mounted a spring-pressed plunger 158. As shown in Fig. 16, the plunger is V-
30 shaped at its lower end and is adapted to engage the roller 155. A lever 159, which is secured to the rock shaft 156 near the front end thereof, is provided with upper and lower arms. The upper arm carries a
35 roller 160 which is adapted to be engaged by a cam plate 161. The cam plate 161 is secured to a cam drum 162 which is mounted on the sleeve 79. The lower arm of the lever 159 carries a roller 163 which is adapted to be engaged by a cam plate 164. The cam plate 164 is secured to a cam drum 165 which is mounted on the shaft 131.
40 When the parts are in the positions shown in Figs. 6, 7 and 16 the sleeve 79 is in motion and continues to turn until the cam plate 161 engages the roller 160 and turns the lever 159 in the clockwise direction, as viewed in Fig. 7, or in the counter-clockwise direction, as viewed in Fig. 16. This
45 movement forces the spring-pressed plunger 158 over the top of the roller 155 and thus tends to swing the lever 154 in the direction to shift the clutch element into position to drive the shaft 149. When the shaft
50 149 is thus driven, the shaft 131 with the

cam drum 165 thereon is driven in the direction indicated by the arrow in Fig. 6. This movement continues until the cam plate 164 engages the roller 163 and swings the lever 169 in the counter-clockwise direction, as viewed in Fig. 7, or in the clockwise direction, as viewed in Fig. 16. In other words, the cam plate 164 serves to restore the lever to the position which is shown in the drawings. The spring-pressed plunger 158 is again moved over the top of the roller 155 and tends to move the lever 154 in the direction to move the clutch element 138 into position to drive the gear wheel 137.
55

Preferably, I do not depend solely upon the shifting of the lever 154 for the timing of the movements of the clutch element 138. As illustrated, the lever 154 is provided with opposite fingers 166 and 167 which are 85 adapted to be engaged, respectively, by latches 168 and 169. The latches 168 and 169 are held in engagement with the fingers by means of a spring member 170. Referring to Fig. 16, it will be seen that the latch 168 serves to prevent the movement of the lever 154 toward the left even after the arm 157 has been moved to its right-hand position. Similarly, the latch 169 serves to prevent the movement of the lever 154 toward the right even after the arm 157 has been moved to its left-hand position. A vertically slidable rod 171, which is normally pressed upward by a spring 172, is provided for releasing the latch 168. The upper end of the rod 171 is engaged by an arm 173 which is mounted on a short transverse rock shaft 174. The rock shaft 174 carries a lever 175 near its front end. A roller, which is adapted to be engaged by a cam projection 176, is mounted on the lever 175. The cam projection 176 is secured to the worm wheel 9. The cam projection 176 is so positioned with respect to the cam plate 161 that the plate first 90 engages the roller 160 and moves the arm 157 into position to shift the lever 154. Subsequently, when the spindle 79 has completed the desired revolution, the cam projection 176 engages the roller on the lever 175, thus turning the rock shaft and the lever 173 and moving the rod 171 to release the latch 168. The latch having been released, the lever 154 turns under the action of the spring-pressed plunger 158 and disengages the clutch element from the gear 137 and engages it with the shaft 149. The latch 169 is mounted on a short transverse rock shaft 177 which carries a lever 178 near its front end. A roller, which is mounted near the upper end of the lever 178, is positioned to be engaged by a cam projection 179 on the cam drum 165. The cam projection 179 is so positioned with respect to the main cam plate 164 that the 95

plate first engages the roller 163 and moves the arm 158 into position to shift the lever 154. Subsequently, when the shaft 131 has completed the desired revolution, the cam 5 projection 179 engages the roller and the lever 178, thus turning the rock shaft 177 to release the latch 169. The latch having been released, the lever 154 turns under the action of the spring-pressed plunger 158 10 and disengages the clutch element from the shaft 149 and engages it with the gear wheel 137. It will be seen that by means of the mechanism described the spindle 79 serves to stop itself after making a complete 15 revolution and to start the shaft 131. Similarly the shaft 131, after making one complete revolution, serves to stop itself and start the spindle 79. Thus these two parts operate alternately in continuous succession. 20 It is desirable to feed the tool longitudinally while out of engagement with the blank, that is, when the tool is opposite the groove between two teeth of the blank. The blank is therefore preferably mounted in 25 the spindle so that at the position of stopping the tool will be opposite a groove. The grooves are helical but the spindle and the blank are supplementally turned at each longitudinal movement. This supplemental 30 turning exactly compensates for the inclination of the grooves and insures the stopping of the blank with a groove opposite the tool.

Preferably the tool is withdrawn at the 35 time of each longitudinal movement, the former pin also being withdrawn from engagement with the former. Such withdrawal is effected by mechanism operated by the shaft 131, the withdrawal being thus 40 properly timed with respect to the feeding movement. An abutment 180, which is engaged by the upper end of a lever 181, is associated with the slide 24. The lever 181 is longitudinally pivoted to the carriage 21. 45 The lower end of the lever is provided with a roller which is adapted to be engaged by a cam plate 182. The cam plate 182 is mounted on a cam disk 183 which is secured to the shaft 131. At the beginning of the 50 rotation of the shaft 131 the cam plate 182 engages the roller on the lever 181 and swings it in a counter-clockwise direction, thus moving the abutment 180 together with the slide 24 toward the front. In this way 55 the tool 25 is withdrawn from the blank and the former pin 27 is withdrawn from the former 26. As the shaft 131 continues to rotate, the cam 130 operates the feeding mechanism in the way already described, 60 and the carriage is moved longitudinally along the bed. After such operation, the cam plate 182 permits the lever 181 to return to the position shown, and the slide 24 is permitted to move rearward carrying the 65 tool 25 and the former pin 27 to their op-

erative positions. It will be seen that by thus withdrawing the former pin from the former at the time of longitudinal movement, I avoid any difficulties incident to forcing the former pin along the former 70 while in contact therewith. If the former pin were maintained in contact with the former at all times difficulty would be experienced in effecting the longitudinal movement, particularly at places where the 75 contour of the former is sharply inclined. Preferably the former pin is restored to engagement with the former by a relatively slow movement with a minimum of pressure, so that there will be no tendency to 80 bend or distort the pin or to secure uneven contact between the pin and the former. For this purpose, I provide a mechanism for returning the carriage that is entirely independent in its operation from the mechanism for withdrawing it. The before mentioned abutment 180 is not connected directly to the slide 24 but is connected to a second slide 184 which is transversely movable independently of the first slide 24. Springs 85 90 95 are interposed between the slide 184 and the carriage 21 and these springs tend to move the slide 184 rearward, thus holding the abutment 180 at all times in engagement with the lever 181.

The two slides 24 and 184 are ordinarily connected by a lock. As shown most clearly in Figs. 7, 8 and 12, the lock includes a plate 186 located in a recess in the top of the slide 24. The plate is provided with a boss 100 which projects downward through a slot in the slide, and threaded into this boss is a vertical stud 187. The stud 187 extends through and closely fits an aperture in the slide 184. Two small bell-crank levers 188 are 105 pivoted to the slide 184. The levers 188 are provided with horizontal upper arms which engage a collar on the stud 187. The lower ends of the levers are adapted to be engaged by a tapered cam bushing 189 which is vertically movable on the stud. When the bushing 189 is in its lower position, as shown, the levers 188 are forced outward, thus drawing the stud 187 downward and forcing the plate 186 into clamping engagement with the slide 110 115 120 125 130 135 140 145 150 155 160 165 170 175 180 185 190 195 198 200 205 210 215 220 225 230 235 240 245 250 255 260 265 270 275 280 285 290 295 300 305 310 315 320 325 330 335 340 345 350 355 360 to a cam disk 195 mounted on the shaft 131. It will be seen that as the shaft 131 rotates, the cam plate 193 engages the roller on the lever 190, thus moving the lever 190 and the 5 cam bushing 189 upward to release the lock. Subsequently the roller is engaged by the cam plate 194, thus moving the cam bushing 189 downward to re-engage the lock.

I have already stated that a supplemental 10 mechanism is provided for returning the slide after it has been withdrawn, in the manner before described. Preferably, in order that the supplemental turning mechanism may operate without being affected in any way by the return movement 15 of the slide 184, and in order further that the slide 24 may be returned with a minimum of effort, I provide a supplemental means for supporting the slide 24 after it 20 has been unlocked from the slide 184. As illustrated, the carriage 21 is provided near its front and rear with transverse pivot pins 196 and 197. The carriage is slotted adjacent the pins, and in these slots are positioned arms 198 and 199 respectively pivoted on the said pins. The arms are respectively provided with rollers 200 and 201 which are adapted to engage the bottom of the slide 24. The arms are connected by pivoted links 25 202, and these links in turn are connected by a transverse yoke 203. The yoke 203 is provided with slots or notches in which fit pivot bosses 204 projecting upward from the lever 190. The result is that when the lever 30 190 is swung upward to release the lock, the arms 198 and 199 are swung in a clockwise direction, thus swinging the rollers 200 and 201 upward so as to lift the slide 24 off from the slide 184 and support it independently. 35 The actual raising of the slide may be but a few thousandths of an inch. Coil springs 205 are provided for returning the slide 24 rearward as soon as it has been released by the lock and elevated by the rollers. Preferably these springs are located in long trans- 40 verse cylindrical apertures 206 in the slide 24. The springs abut at their rear ends against plugs 207 threaded into the apertures, and at their front ends abut against 45 heads 208 on transverse rods 209. The rods 209 extend through central openings in the plugs 207 and are connected at their rear ends with brackets 210 on the carriage 21. Preferably the heads 208 are in the form of 50 pistons and the forward parts of the apertures 206 constitute cylinders 211 in which the heads 208 fit and move. A casting 212, which is provided with a transverse passageway 213, is secured to the slide 24. The 55 passageway 213 communicates at its ends with cylinders 211. A fluid reservoir 214 is also formed in the casting 212. A restricted aperture 215, which is preferably controlled by an adjustable needle valve 216, leads 60 from the passageway 213 into the reservoir 214. An automatic check valve 217 leads from the reservoir 214 back to the passageway 213. The cylinders 211 together with the passageway 213 and a part of the reservoir 214 are filled with a suitable fluid, which 65 is preferably a liquid such as oil. It will be seen that as soon as the slide 21 has been elevated and released from the slide 184, the springs 206 tend to move it rearward. Such tendency, however, is resisted by the 70 engagement of the pistons 208 with the liquid in the cylinders. This engagement forces the liquid out of the cylinders into the passageway 213 and thence into the reservoir 214 through the restricted aperture 215. 75 The liquid can pass through this aperture only relatively slowly, and thus the return movement of the slide is made to take place very slowly. When the slide is moved quickly forward at the time of next feeding, 80 the check valve 217 opens to permit the liquid to flow from the reservoir 14 back to the passageway 213 and the cylinders 211. The slow return movement causes the former pins to engage the former gently and with a minimum force, so that there is little or no tendency to bend or deflect the parts. 85

It will be noted that the several cams 130, 182, 193 and 194 are so positioned in relation to each other that the operations which they 90 respectively control take place in the following order. First the two slides 184 and 24 are moved backward in unison, they being still locked together. Then the slide 24 is unlocked from the slide 184 and is at the same time elevated on the rollers 200 and 201. At or about the same time the carriage is moved longitudinally to feed the tool to a new cutting position. Then the slide 184 is permitted to return to its normal position. In the meantime the slide 24 is being moved slowly rearward under the control of the springs 205 and the fluid regulating mechanism. After 95 the completion of the return movement of the slide 24, the rollers 200 and 201 are lowered and the slide is again locked to the slide 184. 100

I provide a lever 218, which is secured to the rock shaft 191, for manually releasing the slide 24 from the slide 184. A wrench 218^a, as shown in Fig. 8, is provided for moving the lever 218. It will be seen that the operator, by moving the lever 218, can turn the rock shaft, thus raising the cam sleeve 189 and releasing the lock. A segmental gear 219, which is pivoted to the carriage and meshes with a rack 220 secured to the slide, is provided for manually moving the slide 24 forward. A hand lever 221 is 115 connected with the segmental gear 219. It will be seen that by lowering or raising the handle the slide 24 can be moved forward or backward as desired. 120

It is believed that the general operation 130

of the machine will be clear from the foregoing description and that a very brief summary will suffice.

A former 26 is provided having the desired contour and, in the case of an undercut cutter, having the desired relation to the cutter radius, as already explained. A blank is put in place, this blank having been previously grooved and roughed out in any usual or preferred manner. The gearing 78 is adjusted in accordance with the degree of inclination of the helical teeth on the blank and the gearing 56-57 is adjusted, in accordance with the number of teeth on the blank. By means of the hand wheels 40 and 114, the tool is adjusted transversely and longitudinally into engagement with the blank at the right-hand end thereof. Then the machine is started, the spindle 79 and the operating shaft 131 operating alternately in succession. During the rotative movement of the blank relieving movements of the tool are effected as described, thus cutting the desired relief on the teeth of the blank. After one complete revolution of the blank the rotative movement of the spindle is stopped and also the relieving movements of the tool. The carriage is then fed longitudinally toward the left, the blank turning slightly in conformity with the helical teeth. Just prior to the longitudinal movement the tool slide is withdrawn, thus withdrawing the tool from the blank and the former pin from the former. After the longitudinal movement, the tool slide is moved slowly in the opposite direction, thus gently returning the former pin to the former which is engaged at a new position. The tool assumes a corresponding position with respect to the blank. After this movement of the tool and former pin the blank is again rotated through one revolution and these movements are repeated alternately in succession until the blank is completely formed. The relieving movements of the tool are changed in accordance with changes in diameter as already described, to compensate for the non-radial cutting faces on the teeth of the blank. Modifications in the machine and in the arrangement and location of parts may be made within the spirit and scope of my invention, and such modifications are intended to be covered by the appended claims.

55 What I claim is:

1. In a relieving machine for operating on a blank having teeth provided with non-radially arranged cutting faces, the combination comprising a cutting tool, means for effecting feeding movements between said tool and the blank, means for effecting relieving movements of the tool, and means for varying the relieving movements at different blank diameters to compensate for the non-radial tooth faces on the blank.

2. In a relieving machine for operating on a blank having teeth provided with non-radially arranged cutting faces, the combination comprising a cutting tool, means for operating said tool to form a cutter adapted to cut a predetermined non-rectilinear contour, means for effecting relieving movements of said tool, and means for varying the relieving movements at different blank diameters to compensate for the non-radial cutting faces on the teeth of the blank.

3. In a relieving machine for operating on a blank having helical teeth provided with non-radially arranged cutting faces, the combination comprising a cutting tool, means for effecting feeding movements between said tool and the blank, means for effecting relieving movements of the tool, and means for automatically varying the relieving movements at different blank diameters to compensate for the non-radial cutting faces on the blank.

4. In a relieving machine for operating on a blank having helical teeth provided with non-radially arranged cutting faces, the combination comprising a cutting tool, means for operating said tool to form a cutter adapted to cut a predetermined non-rectilinear contour, means for effecting relieving movements of said tool, and means for varying the relieving movements at different blank diameters to compensate for the non-radial cutting faces on the teeth of the blank.

5. In a relieving machine for operating on a blank having undercut teeth, the combination comprising a cutting tool, means for operating said tool to cut a predetermined contour, means for effecting relieving movements of the tool, and means for automatically varying the relieving movements at different blank diameters to compensate for the undercut teeth.

6. In a relieving machine for operating on a blank having undercut helical teeth, the combination comprising a cutting tool, means for effecting feeding movements between the tool and the blank to cut the latter to different diameters, means for effecting relieving movements of the tool, and means for varying the relieving movement at different blank diameters to compensate for the undercut teeth.

7. In a relieving machine for operating on a blank having teeth provided with non-radially arranged cutting faces, the combination comprising a cutting tool, means for effecting feeding movements between the tool and the blank, means for guiding the cutting tool to cut a predetermined contour, means for effecting relieving movements of the tool relative to the blank, and means for varying the relieving movements at different blank diameters to compensate for the non-radial cutting faces on the teeth.

8. In a relieving machine for operating on a blank having teeth provided with non-radially arranged cutting faces, the combination comprising a cutting tool, automatically operating means for governing said tool to for a cutter adapted to cut a predetermined contour, means for effecting relieving movements of the tool in conformity to the teeth on the blank, and means for varying such relieving movements at different blank diameters to compensate for the non-radial cutting faces on the teeth.

9. In a relieving machine for operating on a blank having helical teeth provided with non-radially arranged cutting faces, the combination comprising a cutting tool, means for effecting feeding movements between said tool and the blank, automatically operating means for effecting relieving movements of the tool in conformity with the helical teeth on the blank, and means for varying the relieving movements at different blank diameters to compensate for the non-radial cutting faces on the teeth of the blank.

10. In a relieving machine for operating on a blank having helical teeth provided with non-radially arranged cutting faces, the combination comprising a cutting tool, automatically operating means for effecting feeding movements between said tool and the blank to form a cutter with a predetermined contour differing from a straight line, means for effecting relieving movements of the tool in conformity with the helical teeth on the blank, and means for varying the relieving movements at different blank diameters in conformity with the non-radial cutting faces on the teeth.

11. In a relieving machine for operating on a blank having teeth provided with non-radially arranged cutting faces, the combination with a cutting tool and means for feeding the tool relatively to the blank, of means for effecting an oscillatory transverse movement of the cutting tool to obtain a relieving cut, and means for so modifying the oscillatory movement at different blank diameters as to compensate for the non-radial tooth faces on the blank.

12. In a relieving machine for operating on a blank having teeth provided with non-radially arranged cutting faces, the combination with a cutting tool and means for intermittently and longitudinally feeding the tool relatively to the blank, of means for effecting an oscillatory transverse movement of the cutting tool to obtain a relieving cut, and means for so modifying the oscillatory movement at different blank diameters as to compensate for the non-radial tooth faces on the blank.

13. In a relieving machine for operating on a blank having helical teeth provided with non-radially arranged cutting faces,

the combination with a cutting tool and means for intermittently and longitudinally feeding the tool relative to the blank, of means for effecting a transverse movement of the cutting tool to obtain a relieving cut in conformity to the helical teeth, and means for so modifying the transverse movement at different blank diameters as to compensate for the non-radial tooth faces on the blank.

14. In a relieving machine for operating on a blank having teeth provided with non-radially arranged cutting faces, the combination with a cutting tool, means for intermittently and longitudinally feeding the tool relatively to the blank, and means for withdrawing the tool from engagement with the blank prior to each feeding movement and for restoring the tool into operative position relative to the blank after each feeding movement, of means for effecting an oscillatory transverse movement of the cutting tool to obtain a relieving cut and means for so modifying the oscillatory movement at different blank diameters as to compensate for the non-radial tooth faces on the blank.

15. In a relieving machine for operating on a blank having teeth provided with non-radially arranged cutting faces, the combination with a cutting tool, means for intermittently and longitudinally feeding the tool relatively to the blank, and means for effecting transverse movement of the tool to permit the feeding movements, of means for effecting an oscillatory transverse movement of the cutting tool to obtain a relieving cut and means for modifying the oscillatory movement at different blank diameters to compensate for the non-radial tooth faces on the blank.

16. In a relieving machine for operating on a blank having helical teeth provided with non-radially arranged cutting faces, the combination with a cutting tool, means for intermittently and longitudinally feeding the tool relatively to the blank, and means for withdrawing the tool from engagement with the blank prior to each feeding movement and for restoring the tool into operative position relative to the blank after each feeding movement, of means for effecting oscillating transverse movement of the cutting tool to obtain a relieving cut in conformity to the helical teeth, and means for modifying the oscillatory movement at different blank diameters to compensate for the non-radial tooth faces on the blank.

17. In a relieving machine for operating on a blank having helical teeth provided with non-radially arranged cutting faces, the combination with a cutting tool, means for intermittently and longitudinally feeding the tool relatively to the blank, and means for effecting transverse movement of

- the tool to permit the feeding movements, of means for effecting an oscillatory transverse movement of the cutting tool to obtain a relieving cut in conformity to the helical 5 teeth, and means for modifying the oscillatory movement at different blank diameters to compensate for the non-radial tooth faces on the blank.
18. In a relieving machine for operating 10 on a blank having teeth provided with non-radially arranged cutting faces, the combination comprising a cutting tool, means for effecting feeding movements between the tool and the blank, means comprising a 15 pin and a former for guiding the cutting tool to cut a predetermined contour, means for varying the movements of the cutting tool to relieve the teeth on the blank, and means for varying the relieving movements at different blank diameters to 20 compensate for the non-radial cutting faces on the teeth.
19. In a relieving machine, the combination comprising a rotatable spindle adapted 25 to carry a blank having teeth provided with non-radially arranged cutting faces, a cutting tool, means for effecting relative feeding movement between the tool and the blank longitudinally of the latter, means 30 comprising a pin and former for moving the tool inward or outward during the feeding movement to cut the blank with different diameters, means for effecting relieving movements of the tool in timed relation to 35 the blank rotation, and means for varying the relieving movements of the tool at different blank diameters in conformity with the non-radial tooth faces on the blank.
20. In a relieving machine for operating 40 on a blank having helical teeth provided with non-radially arranged cutting faces, the combination comprising a cutting tool, means for effecting longitudinal feeding movements between said tool and the blank, means comprising a pin and a former for 45 guiding the tool to cut a predetermined non-rectilinear contour, means for varying the movements of the cutting tool to relieve the teeth on the blank, and means comprising 50 a cam member for varying the relieving movements at different blank diameters to compensate for the non-radial cutting faces on the teeth.
21. In a relieving machine, the combination comprising a rotatable spindle adapted 55 to carry a blank having helical teeth provided with non-radially arranged cutting faces, a cutting tool, means for effecting relative feeding movement between the tool 60 and the blank longitudinally of the latter, means comprising a pin and former for moving the tool inward and outward during the feeding movement to cut the blank with different diameters, means for effecting 65 relieving movements of the tool in timed relation to the blank rotation, means for varying the relation between the relieving movements of the tool and the rotative movement of the blank in conformity with helical teeth on the blank, and means for varying the 70 relieving movements of the tool at different blank diameters in conformity with the non-radial tooth faces on the blank.
22. In a relieving machine, the combination comprising a rotatable spindle adapted 75 to carry a blank having teeth provided with non-radially arranged cutting faces, a carriage movable longitudinally of the spindle axis, a transversely movable slide on said carriage, a cutting tool carried by the slide, 80 mechanism for moving the slide and the tool transversely as the carriage moves longitudinally so as to cut the blank with a predetermined contour, mechanism for effecting relieving movements of the tool relatively to 85 the slide in timed relation to the blank rotation, said mechanism serving to accurately time the relieving movements notwithstanding the inward or outward movements of the tool under the control of the 90 contour mechanism, and means for so modifying the movements of such mechanism as to compensate for the non-radial toothed faces on the blank.
23. In a relieving machine for operating 95 on a blank having teeth provided with non-radially arranged cutting faces, the combination comprising a cutting tool, means for effecting longitudinal feeding movements between the tool and the blank, means for 100 varying the transverse position of the tool relative to the blank to permit the longitudinal feeding movements, means comprising a pin and a former for guiding the cutting tool to cut a predetermined contour, 105 means for effecting relieving movements, and means for varying the relieving movements at different blank diameters to compensate for the non-radial cutting faces on the teeth.
24. In a relieving machine for operating 110 on a blank having helical teeth provided with non-radially arranged cutting faces, the combination comprising a cutting tool, means for effecting longitudinal feeding 115 movements between the tool and the blank, means for varying the transverse position of the tool relative to the blank to permit the longitudinal feeding operation, means comprising a pin and a former for guiding 120 the cutting tool to cut a predetermined contour, means for effecting relieving movements of the tool relative to the blank, and means for varying the relieving movements at different blank diameters to compensate 125 for the non-radial cutting faces on the teeth.
25. In a relieving machine for operating 130 on a blank having teeth provided with non-radially arranged cutting faces, the combination comprising a cutting tool, means for

- effecting intermittent feeding movements between the tool and the blank, means comprising a pin and a former for guiding the cutting tool to cut a predetermined contour, 5 means for varying the movements of the cutting tool to relieve the teeth on the blank, and means for varying the relieving movements at different blank diameters to compensate for the non-radial cutting faces on 10 the teeth.

26. In a relieving machine for operating on a blank having teeth provided with non-radially arranged cutting faces, the combination comprising a cutting tool, means for 15 effecting intermittent longitudinal feeding movements between the tool and the blank, means for withdrawing the tool from engagement with the blank prior to each feeding movement and for restoring the tool 20 into operative position relatively to the blank after each feeding movement, a pin and a former member for guiding the tool to cut a predetermined contour, means for 25 effecting relieving movements of the tool relative to the blank, and means for varying the relieving movements to compensate for the non-radial cutting faces on the teeth.

27. In a relieving machine for operating 30 on a blank having helical teeth provided with non-radially arranged cutting faces, the combination comprising a cutting tool, means for effecting intermittent longitudinal feeding movements between said tool and the blank, means for withdrawing the tool 35 from engagement with the blank prior to each feeding movement and for restoring the tool into operative position relative to the blank, means comprising a pin and a former for guiding the tool to cut a predetermined 40 contour, means for effecting relieving movements of the tool in conformity with the helical teeth on the blank, and means for varying the relieving movements at different blank diameters to compensate 45 for the non-radial cutting faces on the teeth.

28. In a relieving machine for operating on a blank having teeth provided with non-radially arranged cutting faces, the combination comprising a cutting tool, means for 50 effecting intermittent longitudinal feeding movements between the tool and the blank, means for varying the transverse position of the tool relative to the blank to permit the longitudinal feeding movements, means 55 comprising a pin and a former for guiding the cutting tool to cut a predetermined contour, means for effecting relieving movements, and means for varying the relieving movements, at different blank diameters to 60 compensate for the non-radial cutting faces on the teeth of the blank.

29. In a relieving machine for operating on a blank having helical teeth provided with, non-radially arranged cutting faces, 65 the combination comprising a cutting tool, 70 means for effecting intermittent longitudinal feeding movements between said tool and the blank, means comprising a pin and a former for guiding the tool to cut a predetermined contour, means for varying the movements of the cutting tool to relieve the teeth on the blank, and means for varying the relieving movements to compensate for the non-radial cutting faces on the teeth in accordance with the variations in diameter 75 of the blank.

30. In a relieving machine for operating on a blank having helical teeth provided with non-radially arranged cutting faces, the combination comprising a cutting tool, 80 means for effecting intermittent longitudinal feeding movements between said tool and the blank, means comprising a pin and a former for guiding the tool to cut a predetermined non-rectilinear contour, means for 85 varying the movements of the cutting tool to relieve the teeth on the blank, and means for varying the relieving movements to compensate for the non-radial cutting faces on the teeth in accordance with the variations in diameter 90 of the blank.

31. In a relieving machine for operating on a blank having helical teeth provided with non-radially arranged cutting faces, the combination comprising a cutting tool, 95 means for effecting intermittent longitudinal feeding movements between the tool and the blank, means for varying the transverse position of the tool relative to the blank to permit the longitudinal feeding movements, means comprising a pin and a former for guiding the cutting tool to cut a predetermined 100 non-rectilinear contour, means for effecting relieving movements, and means for varying the relieving movements to compensate at different blank diameters for the non-radial cutting faces on the teeth.

32. In a relieving machine for operating on a blank having helical teeth provided with non-radially arranged cutting faces, 110 the combination comprising a cutting tool, means for effecting intermittent longitudinal feeding movements between said tool and the blank, means for withdrawing the tool from engagement with the blank prior to 115 each feeding movement and for restoring the tool into operative position relative to the blank, means comprising a pin and a former for guiding the tool to cut a predetermined non-rectilinear contour, means for effecting relieving movements of the tool in conformity with the helical teeth on the blank, and means for varying the relieving movements at different blank diameters to 120 compensate for the non-radial cutting faces on the teeth.

33. In a relieving machine for operating on a blank having helical teeth provided with non-radially arranged cutting faces, the combination comprising a cutting tool, 130

- means for effecting longitudinal feeding movements between the tool and the blank, means for varying the transverse position of the tool relative to the blank to permit the longitudinal feeding movements, means comprising a pin and a former for guiding the cutting tool to cut a predetermined contour, means for effecting relieving movements, and means for varying the relieving movements at different blank diameters in accordance with the contour of the former to compensate for the non-radial cutting faces on the teeth.
34. In a relieving machine for operating on a blank having helical teeth provided with non-radially arranged cutting faces, the combination comprising a cutting tool, means for effecting longitudinal feeding movements between the tool and the blank, means for varying the transverse position of the tool relative to the blank to permit the longitudinal feeding movements, means comprising a pin and a former for guiding the cutting tool to cut a predetermined non-rectilinear contour, means for effecting relieving movements, and means for varying the relieving movements in accordance with the contour of the former to compensate for the non-radial cutting faces on the teeth.
35. In a relieving machine for operating on a blank having teeth provided with non-radially arranged cutting faces, the combination comprising a cutting tool, means for effecting intermittent longitudinal feeding movement of the cutting tool relative to the cutter blank, means for withdrawing the tool from engagement with the blank prior to each feeding movement and for restoring the tool into operative position relative to the blank after each feeding movement, means for effecting an oscillatory transverse movement of the cutting tool to obtain a relieving cut, and means comprising a pin and cam groove connection for so modifying the oscillatory movement of the tool as to compensate for the non-radial tooth faces on the blank.
36. In a relieving machine for operating on a blank having helical teeth provided with non-radially arranged cutting faces, the combination comprising a cutting tool, means for effecting intermittent longitudinal feeding movement of the cutting tool relative to the cutter blank, means for withdrawing the tool from engagement with the blank prior to each feeding movement and for restoring the tool into operative position relative to the blank after each feeding movement, means for effecting relieving movements of the tool in conformity to the helical teeth on the blank, and means comprising a pin and groove connection for so modifying the relieving movement of the tool as to compensate for the non-radial tooth faces on the blank.
37. In a relieving machine for operating on a blank having helical teeth provided with non-radially arranged cutting faces, the combination with a cutting tool, and means for effecting intermittent longitudinal feeding movement of the cutting tool relative to the blank, of means for withdrawing the tool from engagement with the blank prior to each feeding movement and for restoring the tool into operative position therewith after each feeding operation, means for effecting relieving movements, and means comprising a shaft having cam grooves formed therein for so varying the relieving movements as to compensate for the non-radial cutting faces on the blank.
38. In a relieving machine for operating on a blank having helical teeth provided with non-radially arranged cutting faces, the combination with a cutting tool, and means for effecting intermittent longitudinal feeding movements of the cutting tool relative to the blank, of means for withdrawing the tool from engagement with the blank prior to each feeding movement, means for effecting relieving movements of the tool in conformity with the helical teeth on the blank, and means comprising a shaft having cam grooves therein for so varying the relieving movements as to compensate for the non-radial cutting faces on the blank.
39. In a relieving machine, the combination with a rotatable spindle adapted to carry a blank having teeth provided with non-radially arranged cutting faces, a cutting tool, and means for effecting feeding movements of the tool relatively to the blank, of means comprising a relieving cam member driven by a transversely-mounted cam shaft for effecting relieving movements of the tool relatively to the blank in conformity to the teeth on the blank while compensating such movements for the non-radial cutting faces on the teeth of the blank.
40. In a relieving machine, the combination with a rotatable spindle adapted to carry a blank having helical teeth provided with non-radially arranged cutting faces, a cutting tool, and means for effecting feeding movements between the tool and the blank, of means comprising a relieving cam member driven by a transversely-mounted cam shaft for effecting relieving movements of the tool in conformity to the helical teeth on the blank and for compensating such movements in accordance with the non-radial cutting faces on the blank.
41. In a relieving machine, the combination with a rotatable spindle adapted to carry a blank having teeth provided with non-radially arranged cutting faces, a cutting tool, means for effecting automatic longitudinal feeding movements of the tool relatively to the blank, and means for effecting transverse movements of the tool to

5 permit such feeding movements, of means comprising a relieving cam member driven by a transversely-mounted cam shaft for effecting relieving movements of the tool and for compensating such movements in accordance with the non-radial cutting faces on the teeth of the blank.

42. The combination comprising a rotatable blank having teeth provided with non-10 radially arranged cutting faces, a cutting tool, means for effecting feeding movements between the tool and the blank, automatically-acting mechanism for effecting relieving movements of the tool, and driving 15 means for said relieving mechanism comprising cam grooves formed in a transverse shaft, said grooves being so formed as to vary the relieving movements to compensate for the non-radial cutting faces on the 20 teeth of the blank.

43. The combination comprising a rotatable spindle adapted to carry a blank having teeth provided with non-radially arranged cutting faces, a cutting tool, means 25 for effecting intermittent feeding movements of the tool longitudinally of the blank, automatically-acting mechanism for effecting regular relieving movements of the tool, and driving means for the relieving 30 mechanism comprising cam grooves formed in a transverse shaft, said grooves being so formed as to vary the relieving movements to compensate for the non-radial cutting faces on the teeth of the blank.

44. The combination comprising a rotatable spindle adapted to carry a blank having helical teeth provided with non-radially arranged cutting faces, a cutting tool, means 35 for feeding the tool longitudinally of the blank, automatically-acting mechanism for effecting regular relieving movements of the tool in conformity to the helical teeth on the blank, and driving means for the relieving 40 mechanism comprising cam grooves formed in a transversely-mounted shaft, said grooves being so formed as to vary the relieving movements to compensate for the non-radial cutting faces on the teeth of the blank.

45. The combination comprising a rotatable spindle adapted to carry a blank having teeth provided with non-radially arranged cutting faces, a cutting tool, means 50 for effecting intermittent regular feeding movements of the tool relatively to the blank, means for effecting transverse movement of the tool to permit such feeding movements, automatically-acting mechanism 55 for effecting regular relieving movements 60 of the tool supplemental to the transverse

movements, and driving means for the relieving mechanism comprising cam grooves formed in a transversely-mounted shaft, said grooves being so formed as to vary the relieving movements to compensate for the 65 non-radial cutting faces on the teeth of the blank.

46. In a relieving machine, the combination comprising a rotatable spindle adapted to carry a blank having teeth provided with 70 non-radially arranged cutting faces, driving means for rotating said spindle and the blank, a cutting tool, means for effecting feeding movements between the tool and the blank, means comprising a cam member 75 for effecting relieving movements of the tool, and means comprising a shaft having cam grooves formed therein for connecting said cam member to the driving means and for compensating the relieving movements 80 at different blank diameters of the non-radial cutting faces on the teeth of the blank.

47. In a relieving machine, the combination comprising a rotatable spindle adapted 85 to carry a blank having helical teeth provided with non-radially arranged cutting faces, driving means for rotating said spindle and the blank, a cutting tool, means for effecting feeding movements between the 90 tool and the blank, and means comprising a cam member for effecting relieving movements in conformity with the helical teeth on the blank, said relieving means also including a shaft having cam grooves formed 95 therein to connect the cam member to said driving means and to compensate the relieving movement at different blank diameters for the non-radial cutting faces on the 100 teeth of the blank.

48. In a relieving machine, the combination comprising a rotatable spindle adapted to carry a blank having teeth provided with non-radially arranged cutting faces, driving 105 means for rotating said spindle and the blank, a cutting tool, means for effecting intermittent feeding movements of the tool relative to the blank, means comprising a cam member for effecting relieving movements of the tool, and means comprising a 110 shaft having cam grooves formed therein to connect said cam member to said driving means and to compensate the relieving movement at different blank diameters for the non-radial cutting faces on the teeth of 115 the blank.

In testimony whereof, I hereto affix my signature.

FRIEDERICH MÜLLER.

Certificate of Correction.

It is hereby certified that in Letters Patent No. 1,443,639, granted January 30, 1923, upon the application of Friederich Müller, of Hartford, Connecticut, for an improvement in "Relieving Machines," errors appear in the printed specification requiring correction as follows: Page 12, line 6, claim 8, for the word "for" read *form*; same page, line 118, claim 16, for the word "oscillating" read *oscillatory*; and that the said Letters Patent should be read with these corrections therein that the same may conform to the record of the case in the Patent Office.

Signed and sealed this 20th day of March, A. D., 1923.

[SEAL.]

KARL FENNING,
Acting Commissioner of Patents.
